NATHAN L. GOLDBERG, OF NEW YORK, N. Y.

DESIGN FOR A MEZUZAH

Application filed December 24, 1928. Serial No. 29,400. Term of patent 14 years.

To all whom it may concern:

Be it known that I, NATHAN L. GOLDBERG, a citizen of the United States, and resident of New York, in the county of New York and State of New York, have invented a new, original, and ornamental Design for Mezuzahs, of which the following is a specification.

In the accompanying drawing forming a material part of this disclosure:—

Fig. 1 is a front elevational view of a mezuzah, showing my design.

Fig. 2 is a side elevational view thereof.

I claim:—

The ornamental design for a mezuzah, as shown.

Signed at New York, in the county of New York and State of New York, this 21st day of December, A. D. 1928.

NATHAN L. GOLDBERG.
